DUMP BAILER

William C. Gipson, Jacksboro, Tex., assignor of
one-half to Wesley Senkel, Graham, Tex.

Application August 9, 1946, Serial No. 689,613

5 Claims. (Cl. 166—19)

1

My present invention relates to an improved dump bailer bottom of the type designed for use in depositing material such as cement in the bottom of a well casing, and the dump bailer bottom of my invention is so arranged as to be operative to dump the material either on the bottom of the well or above the bottom as circumstances require.

In the accompanying drawings I have illustrated one complete example of the physical embodiment of my invention according to the best mode I have thus far devised but it will be understood that various changes and alterations may be made in the exemplified structure within the scope of the appended claims.

In the drawings:

Figure 1 is a front elevational view of an embodiment of my invention shown in position within a sectional well casing.

Figure 2 is a vertical sectional view at line 2—2 of Figure 1.

Figure 3 is a front elevational view showing the sliding strap out of engagement with the tripping finger.

Figure 4 is a vertical sectional view thereof.

Figure 5 is a vertical sectional view of the upper portion of the apparatus showing the container with its door in open position.

Figure 6 is a horizontal sectional view at line 6—6 of Figure 1.

Figure 7 is a detail view of the tripping mechanism; and

Figure 8 is a side elevational view of my improved dump bailer bottom.

Referring now to the drawings wherein like characters indicate like parts, I have illustrated the present embodiment of my invention as comprising a cylinder 4 having an apertured lifting ear 5 fixed to the upper edge thereof. The ear 5 is adapted to receive conventional hoisting means whereby the cylinder 4 is adapted to be lowered within a conventional well casing as 2.

The cylinder 4 is of such diameter as will permit ready passage through the casing and is formed with opposed surface notches 6 and 8, which serve as a window to gain access to the door 16 for normally closing the door before using or filling the container or to remove the hinge pin 18 for the door 16 if repair is necessary. The cylinder 4 is also provided with a vertical slot 10 for a purpose to be later described.

Within the cylinder 4 I employ a cylindrical container 12 which is provided with an upper outwardly flared end portion 14 that is welded or otherwise secured to the cylinder 4 slightly

below the upper edge thereof as shown in Figures 2, 4 and 5 respectively, and this container is provided at the bottom thereof with a door 16 pivotally secured to the lower edge of the container as at 18 as shown in the above figures.

Adapted for attachment to the exterior of the container 12 and vertically movable in the slot 10 in the cylinder 4 I utilize the sliding U-shaped strap 20 formed with slots 22 and 24 through which the screws 26 extend to secure the strap to the container 12.

The strap is offset outwardly at 28 to form the inner cam surfaces 30 and 31, and extending transversely of and mounted in the cylinder 4 is a pin 33 on which is pivotally mounted the cam dog 32. The cam dog 32 is positioned within the offset 28 so that the upper end thereof may engage the lower surface of the marginal edge of the door 16 in opposed relation to the pivot 18, maintaining the bottom in closed relation to the lower end of the container 12, the cam surface 30 engaging the cam dog 32 to retain it in the above mentioned position when the U-shaped strap 20 is in its lower position as shown in Figure 2. In the vertical movement of the strap hereinafter described the cam surface 31 engages the lower end of the cam dog 32 to move the dog on the pin 33 to disengage the upper end of the dog from the door 16 to permit the opening of the door 16 of the container 12 as shown in Figure 4.

The lower portion of the strap 20 is bent into U-shape as at 36, the offset 34 permitting the strap to enter the slot of the cylinder 4 and the slotted end 38 of the strap is secured by a screw 40 which passing through the slotted end 38 is received in the interior surface of the opposite side of the wall of the cylinder 4.

A V-shaped stirrup strap 42, constructed of spring steel, is provided with opposed straight portions 44 and 46. The portions 44 and 46 frictionally engage the inner surface of the casing 2 to retain the strap 42 in sliding reciprocal engagement with the inner surface of the casing 2. The upper ends of the portions 44 and 46 are inset and enter the cylinder 4 and are provided with the elongated slots 48 and 50 respectively. A pin 52 extending transversely of the cylinder 4 and passing through the slots 48 and 50 detachably secures the strap 42 to the lower end of the cylinder 4. The strap 42 is used only when the contents of the container 12 are to be dumped above the well bottom, otherwise the U-shaped strap 20 alone is employed to dump the contents of the container 12 at the well bottom. The dump bailer is lowered into the well to any

desired location with the parts in the position shown in Figs. 1 and 2, cylinder 4 is now raised to cause portion 36 of the strap 20 to engage the finger 54 hingedly mounted at 56 in the yoke 58 on the V-shaped strap 42. The finger 54 is pivoted for movement only above the horizontal so that the strap 20 will pass above the finger 54 as shown in Figure 3. When the cylinder 4 is now lowered, the frictional engagement of the portions 44 and 46 with the casing 2 will retain the strap 42 in fixed relation relative to the casing 2 so that during the downward movement of strap 20, the finger 54 will be engaged by the lower portion of the U-shaped strap to elevate the strap 20 and actuate the cam dog to disengage the dog from the bottom of the door 16 to permit the door of the container to open and the contents to be dumped.

Under ordinary circumstances it will be found desirable to dump the material at the bottom of the well in which case the V-shaped strap and its finger 54 are omitted as the cylinder is lowered within the well casing, and therefore the bottom portion of the U-shaped strap 20 will engage the bottom of the well directly and through the same mechanism of the cam and cam dog, the door will be opened and the material will fall through the cylinder 4 directly to the well bottom. However when a slow hardening material is used and the strap 20 will not engage a surface firm for its actuation the V-shaped stirrup strap 42 will be used, as it does not have to contact firm bottom surface to cause the contents of the container 12 to be dumped.

When the dump bailer is once opened mechanically it is impossible for the door to close as when the dump bailer is being elevated to the surface.

Furthermore in being lowered into the well casing there is no danger of the door being opened by contact with the fluid surface as the passage of the dump bailer through such fluid aids in pressing upon the door to maintain it closed until positively tripped by operation of the V-shaped strap if used, or by the U-shaped strap alone if the V-shaped strap is not used.

Having thus fully described my invention what I claim as new and desire to secure by Letters Patent is:

1. A dump bailer bottom for use in a well casing comprising a hollow cylinder opening at its lower end to provide an exit or discharge opening, said cylinder being formed with intermediate laterally opposed slots and a vertical slot, a material container secured within the cylinder slightly below the open upper edge thereof, a bottom door pivotally mounted on the lower periphery of the container, a strap mounted on the container for vertical movement in the vertical slot in the cylinder, pivoted means carried by the cylinder adjacent the free edge of the door and adapted to engage the door to retain the door in closed position, said means is engaged by said strap upon upward vertical movement of the strap relative to the cylinder to pivot said means to disengage said means from contact with said door to permit opening of the door, strap engaging means mounted for upward vertical movement on the lower end of the cylinder for engaging the strap to cause upward vertical movement of the strap relative to the cylinder, said strap engaging means having frictional engagement with the well casing in which the bailer is being used and having limited lost vertical motion with respect to said

strap, said opposed slots being located in said cylinder immediately below the pivotal mounting for the bottom door of the container to permit closing of the door before using or filling the container.

2. A dump bailer bottom for use in a well casing comprising a hollow cylinder open at its lower end to provide an exit or discharge opening, said cylinder being formed with intermediate laterally opposed slots and a vertical slot, a material container secured within the cylinder slightly below the open upper edge thereof, a bottom door pivotally mounted on the lower periphery of the container, a strap mounted on the container for vertical movement in the vertical slot in the cylinder, an offset in the strap forming upper and lower cam faces, cam means carried by the cylinder adjacent the free edge of the door and positioned intermediate of said upper and lower cam faces, said cam means engaging and retaining the door in closed position when the upper cam face engages said cam means, said cam means operable upon engagement with the lower cam face to release the door, strap engaging means mounted for vertical movement on the lower end of the cylinder for engaging the strap to cause upward vertical movement of the strap relative to said cylinder to operate said cam means to release the door, and said strap engaging means having limited lost motion vertical movement with respect to said strap, and said opposed slots being located in said cylinder immediately below the pivotal mounting for the bottom door of the container to permit closing of the door before using or filling the container.

3. A dump bailer bottom for use in a well casing comprising a hollow cylinder open at its lower end to provide an exit or discharge opening, said cylinder being formed with intermediate laterally opposed slots and a vertical slot, a material container secured within the cylinder slightly below the open upper edges thereof, a bottom door pivotally mounted on the lower periphery of the container, a strap mounted on the container for vertical movement in the vertical slot in the cylinder, an offset in the strap forming cam faces, a cam dog pivotally mounted on the cylinder adjacent the free end of the door adapted to engage said door and retain it in closed position, said dog being operable through engagement therewith of a cam face of the strap when the strap is moved upwardly relative to the cylinder to disengage from and permit opening of the door, strap engaging means mounted for vertical movement on the lower end of the cylinder for engaging the strap to cause upward vertical movement of the strap relative to the cylinder, said strap engaging means having frictional engagement with the well casing in which the bailer is being used and having limited lost motion vertical movement with respect to said strap, and said opposed slots being located in said cylinder immediately below the pivotal mounting for the bottom door of the container to permit closing of the door before using or filling the container.

4. In a dump bailer bottom for use in a well cylinder the combination with a hollow cylinder open at its lower end to provide an exit or discharge opening, said cylinder being formed with laterally opposed notches and a vertical slot, a material container secured within the cylinder slightly below the open upper edges thereof, a door for the bottom of the container pivotally

mounted on the lower periphery of the container, of a strap mounted on the container for vertical movement in the slot in the cylinder, pivot means carried by the cylinder for engaging the door to retain it in closed position, means on the strap engaging said pivot means to disengage said pivot means from said door to permit the opening of the door in response to upward vertical movement of the strap relative to the cylinder, and said strap having a lower U-shaped bend forming a well bottom engaging portion for causing upward vertical movement of the strap with relation to the cylinder upon contact of the U-shaped bend with the well bottom, and said opposed notches being located in said cylinder immediately below the pivotal mounting for the bottom door in the container to permit closing of said door before using or filling the container.

5. In a dump bailer bottom for use in a well casing the combination with a hollow cylinder open at its lower end to provide an exit or discharge opening, said cylinder being formed with laterally opposed notches and a vertical slot, a material container secured within the cylinder slightly below the open upper edges thereof, and a door for the bottom of the container pivotally mounted on the lower periphery of the container, said opposed notches being located in said cylinder immediately below the pivotal mounting for the bottom door in the container to permit closing of said door before using or filling the container, a strap mounted on the cylinder for vertical movement in the slot in the cylinder, means carried by the cylinder for engaging the door to

10

retain it in closed position, offset means on the strap engaging said first means to disengage said first means from said door to permit the opening of the door in response to upward vertical movement of the strap relative to the cylinder, the lower end of the strap being bent upon itself to form a horizontal contact portion, a V-shaped strap slidably mounted in the cylinder and adapted to have constant frictional engagement with the casing, and a hinged finger pivotally mounted on the V-shaped strap in the path of the first strap for pivotal movement above the horizontal only so said finger is engageable with the contact portion of the strap upon downward movement of the strap to cause upward vertical movement of the strap at any desired distance above the bottom of the well, and said V-shaped strap having lost motion vertical movement with respect to said first strap or downward movement of said V-strap relating to said cylinder.
